The ornamental design for a case for holding hand tools, as shown and described.

DESCRIPTION

FIG. 1 is a front view of a case for holding hand tools, showing my new design;

FIG. 2 is a right elevational view thereof;

FIG. 3 is a rear view thereof;

FIG. 4 is a left elevational view thereof;

FIG. 5 is a plan view thereof;

FIG. 6 is a front view thereof similar to FIG. 1, but with a handle and clips forming part of my case for holding hand tools, being shown in the open position;

FIG. 7 is a front view thereof similar to FIG. 6, but with just the handle being shown in the open position; and,

FIG. 8 is a right elevational view thereof similar to FIG. 2, but with just the handle being shown in the open position of FIG. 7.

Fig.1.

Fig. 2.

Fig. 3.

Fig. 4.
